By L. B. Singer, Atty.

UNITED STATES PATENT OFFICE.

HARRY HERBERT PAYNE, OF BIRMINGHAM, ENGLAND, ASSIGNOR OF TWO-THIRDS
TO JOHN WHITE, OF BIRMINGHAM, ENGLAND.

DROP-DOWN GUN AND RIFLE.

1,392,024.

Specification of Letters Patent. Patented Sept. 27, 1921.

Application filed August 21, 1919. Serial No. 319,025.

To all whom it may concern:

Be it known that I, HARRY HERBERT PAYNE, a subject of the Kingdom of Great Britain, residing at 30 Bristol road, Bourne-
5 brook, Birmingham, in the county of Warwick, England, have invented certain new and useful Improvements in or Relating to Drop-Down Guns and Rifles, of which the following is a specification.

10 This invention comprises certain improvements in, or relating to, guns and rifles adapted to be "broken" at the breech for loading.

According to the present invention I employ a sliding or longitudinally moving hammer adapted to be cocked or retracted by the operation of loading.

I also provide hammer actuating mechanism of a telescopic or extensible character 20 adapted to be extended against the resistance of a spring. The opening of the breech causes one element of this telescopic mechanism connected with the hammer to come into a position in which it is retained by the 25 sear, and the closing of the gun displaces the other element of the mechanism against the resistance of the said spring.

Advantageously I form or drill a pocket in the frame or body of the gun to accommodate the hammer actuating mechanism. This pocket serves as a guide both for the telescopic members and the sliding or longitudinally moving hammer.

In order that this invention may be clearly 35 understood and readily carried into practice, reference may be had to the appended explanatory sheet of drawings, upon which:—

Figure 1 is a sectional elevation of a part of a gun embodying the present invention.

40 Fig. 2 a similar view illustrating the parts shown in Fig. 1, but with the hammer in the cocked position.

Fig. 3 shows the parts illustrated in Figs. 1 and 2, but with the hammer in the position 45 which it assumes after it has been released by the sear.

In a convenient embodiment of the present invention, *a* is the firing pin which is carried by a sliding or longitudinally moving hammer *b* which is actuated by mechanism of a telescopic or extensible character adapted to be extended against the resistance of a spring. In the arrangement shown the hammer *b* itself forms part of one member 55 of the said telescopic or extensible mecha-

nism and is adapted to be retained by the sear *c*. In the cocking process consequent upon the closing of the gun the other element *d* of the hammer actuating mechanism is displaced against the resistance of the 60 said spring *e*. Upon the hammer being released by actuation of the sear *c* by the trigger (not shown) the hammer *b* is displaced under the influence of the said spring *e* to cause the firing pin *a* to strike the cap 65 of the cartridge.

A second spring *f*, which I term the rebound spring, is located in alinement with, and adapted to be compressed by, the displacement of the telescopic element *d* in the 70 cocking operation, while upon the opening of the gun it is released and causes the telescopic elements and the hammer *b* to rebound into a position in which the hammer *b* is retained by the sear *c*.

The hammer actuating mechanism above described is advantageously located, as shown, in a pocket or blind hole drilled longitudinally from the rear in the frame or body *g* of the gun. An aperture *h* may 80 be provided extending from the said pocket to the upper face of said frame or body, through which aperture the cocking operation is effected. In this aperture a lever *i* is located and pivoted at its front extremity 85 to the frame. This lever has a depending projection *j* which is adapted to engage with a cam surface *k* provided on the fore part of the telescopic bolt. When the gun is open the said lever *i* projects above the 90 upper face of the frame. When in the operation of closing the gun the rear part of the barrel descends upon said upper face of the frame, this lever *i* is depressed with the result that its depending part is caused 95 to forwardly actuate the one telescopic element *d* of the bolt against the resistance of the rebound spring *f* in front of the same, to thereby compress the hammer actuating spring *e*.

The sear which is controlled by a suitable spring provision *l* is pivoted below the rear part of the hammer *b* and has an upward tooth *m* adapted to engage with a ratchet tooth or shoulder upon the hammer 105 *b* so that in the above described cocking operation the hammer is retained by the sear in its retracted position. Upon actuation of the sear by the trigger the hammer advances under the impulse of the spring *e* 110

and strikes the cartridge. Upon opening the gun lever *i* rises, releasing the spring *f* which forces the telescopic members back into the position shown in Fig. 1 in which 5 the hammer *b* is retained by the sear *c*.

The hammer may comprise a vertically located block integral at its lower part with the one telescopic element and carrying at its other part the firing pin *a*. This block 10 is adapted to be located in a cavity *n* in the rear face of the frame, the base of said cavity being adapted to function as a stop limiting the forward movement of the hammer.

15 The telescopic member integral with the hammer comprises a forwardly projecting integral boss upon the said block into which boss the rear extremity of a rod *o* is screwed. This rod is at its fore extremity provided 20 with an enlargement *p* and is encircled by the coiled spring *e* which is located within the other telescopic member *d* which is in the form of a sleeve having at its rear extremity an internal shoulder with which the rear 25 extremity of the spring engages. Into the fore extremity of this sleeve a plug *q* is screwed. An aperture *r* is cut through this sleeve and laterally into the screwed plug, said aperture terminating at the front with 30 the surface *k* which is inclined downwardly. This surface forms the cam which is engaged by the lever *i* which is actuated upon the closing of the barrel.

What I claim as my invention and desire 35 to secure by Letters Patent is:—

1. In a gun adapted to be broken at the breech for loading, a breech piece, a hammer having a bolt mounted for axial movement in the breech piece, a spring on the bolt to 40 cause the hammer to strike, a movable member arranged to compress said spring when said member is moved in one direction, a lever mounted in the breech piece and ar-

ranged for movement by the barrel when the gun is closed, to cause said movable member 45 to compress said spring, and a second spring to move said movable member to move the hammer to cocked position.

2. In a gun adapted to be broken at the breech for loading, a breech piece, a hammer having a bolt mounted for axial movement in the breech piece, a spring on the bolt to cause the hammer to strike, a movable member arranged to compress said spring when 50 said member is moved in one direction, a lever mounted in the breech piece and arranged for movement by the barrel when the gun is closed, to cause said movable member to compress said spring, a second spring to move said movable member to move the hammer to cocked position, and a spring actuated 55 sear to hold the hammer in cocked position.

3. In a gun adapted to be broken at the breech for loading, a breech piece, a hammer having a bolt mounted for axial movement in the breech piece, a spring coacting with the bolt to cause the hammer to strike, a movable member arranged to compress said spring when 60 said member is moved in one direction, means, arranged for movement by the barrel when the gun is closed, to cause said movable member to compress said spring, and means to move the hammer to cocked position when the gun is broken.

4. In a gun adapted to be broken at the breech for loading, hammer-actuating mechanism of a telescopic or extensible character, the members of which are adapted to be extended automatically, a resilient means co- 65 acting with said element in the operation of closing the breech, and a cocking spring operative when the breech is opened.

In witness whereof I have hereunto set my hand.

HARRY HERBERT PAYNE.
